HOVER TOP OR SIMILAR ARTICLE

Elmer W. Swanberg, 1420 E. 58th Ave.,
Spokane, Wash. 99203

Filed Feb. 10, 1969, Ser. No. 15,714

Term of patent 14 years

Int. Cl. D21—02

U.S. Cl. D34—15

FIG. 1 is a side elevational view of a hover top or similar article embodying my new design.

FIG. 2 is a front perspective view of the hover top or similar article embodying my new design as viewed from the top;

FIG. 3 is a perspective view of the within invention as viewed from the bottom and side opposite FIG. 2.

I claim:

The ornamental design for a hover top or similar article, substantially as shown and described.
